FRANK AUSTIN,

By Robert L. Dennis
Attorney

UNITED STATES PATENT OFFICE

2,450,103

SUCKER ROD BACKOFF WHEEL

Frank Austin, Long Beach, Calif.

Application September 13, 1945, Serial No. 616,116

2 Claims. (Cl. 255—35)

1

This invention relates to a backoff wheel used for unscrewing sucker rod sections when removal of the same from a well is necessary.

In the operation of a pumping oil well, it is necessary to have a string of sucker rods running from the top of the well to the pump which is seated on the lower end of the tubing. In a deep well, these rods are larger at the top of the string than at the lower end due to the greater load being placed on the top rods.

When a pump is to be changed, these rods are pulled out in sections of regular length, usually 90 feet, and a new pump installed and the string of rods are then replaced. All rods except special ones used for fishing jobs are connected by right hand threads every thirty feet. Sometimes, when it becomes necessary to pull the rods it is found that the pump cannot be unseated from the bottom due to scale or sand that has settled around the pump barrel. In this case the rods have to be turned to the left until they become unscrewed at some point down the hole and the rods which are recovered in this manner are then pulled out. The tubing is then pulled until the upper end of the string of rods is exposed again and the operation started over again until all the rods have been stripped out.

During these backoff operations it is desirable to place strain in the rods before turning to the left. This places more strain on the upper end of the string of rods than is on the deeper couplings, the idea being that the rods will part at a greater depth and more of them removed at one time. After a number of turns are put in the rods it is sometimes desirable to lessen the strain on the rods with the torque still in them. This will often cause the rods to part instantly. Since the rods do not often become unscrewed without considerable effort, it is desirable to provide a tool that can be placed on the rods and the rods rotated with a minimum of danger to the crew.

Tools now in use have not been found satisfactory and it is therefore one object of the invention to provide a device which may be used for unscrewing sucker rods when a string of rods cannot be pulled from a well, the tool not being intended for use as a rod wrench under normal conditions.

Another object of the invention is to provide a device which will be under complete control of the operator at all times during its use in backing off the rods.

Another object of the invention is to provide a device including in its construction, a wheel formed with a radially extending slot so that it

2

may be disposed about a string of sucker rods in position for use and the sucker rod firmly clamped at the center of the wheel.

Another object of the invention is to provide the wheel with rod-clamping means so formed that rods of different diameters may be gripped and the wheel firmly secured to them.

Another object of the invention is to provide improved means for rotatably mounting the wheel and improved means for controlling retrograde rotation of the wheel after it has been turned in a direction for unscrewing the sucker rod sections from each other.

Another object of the invention is to provide latch means for the wheel carried by anchoring means for the wheel mounting and also a brake, movable into and out of position for gripping the under face of the wheel and firmly holding the wheel against turning when so desired.

Another object of the invention is to provide a device of this character which is of simple construction, very easy to operate and not liable to get out of order and become broken when subjected to strains during use.

The invention is illustrated in the accompanying drawings wherein:

Figure 1 is a top plan view of the device shown applied to a sucker rod;

Figure 2 is a bottom plan view of the tool; Figure 3 is a side elevation showing the tool applied to a sucker rod;

Figure 4 is a sectional view taken along line 4—4 of Figure 1;

Figure 5 is a fragmentary sectional view taken along line 5—5 of Figure 4;

Figure 6 is a sectional view taken along line 6—6 of Figure 4; and

Figure 7 is a view similar to Figure 6 showing the latch depressed to a position for releasing the wheel.

This improved tool is formed of strong metal and has a wheel 1 provided with spokes 2 extending radially of the wheel between the hub 3 and the rim 4 of the wheel. The hub is in the form of a flat disk and at its center is formed with an opening 5 to receive a sucker rod 6 which is engaged in this opening by passing it through a slot 7 extending radially of the wheel and bordered along its sides by strips 8 which take the place of one of the spokes.

A circular mounting ring or collar 9 is disposed under the wheel concentric thereto and has a removable lower section 9' held in place by screws 10 which engage in threaded openings 11 and firmly hold the ring to the wheel. Before the sec-

tion 9' is applied, a ring 12 is set in place about the collar 9 and fits loosely in the groove 13 extending about the collar and from this ring 12 extends a plate 14 having its outer end portion formed with side openings 15, so that by passing anchoring cables 16 through these openings the plate and the ring 12 may be firmly mounted between suitable supports and the ring prevented from having rotary movement. A slot 18 is formed through the ring 12 diametrically opposite the plate 14 and when the wheel is turned to the position shown in Figures 1 and 2 and its slot 7 disposed in registry with the slot 18 the sucker rod may be engaged in the outer end portion of slot 7 and the wheel shifted into place about the sucker rod.

The wheel must be firmly secured to the sucker rod in order to turn the rod when the wheel is turned and in order to do so there has been provided a clamp having a stationary jaw 19 and a companion jaw 20. The jaw or block 19 is secured to the hub or plate 3 by screws 21 and at its inner side is formed midway its length with a recess 22 to receive the sucker rod and at its ends with flanges or ribs 23 about which engage the hook-shaped end portions 24 of the jaw or block 20. Midway the length of its inner side face, the block 20 is formed with a recess 25 in which is fitted a key 26 having an edge face presented towards the sucker rod formed with longitudinally extending teeth for biting engagement with the sucker rod when a set screw 27 engaged in a threaded opening 28 in the block is turned in a tightening direction.

The key has its outer side edge face stepped, as shown in Figure 4, so that it is progressively reduced in thickness towards its lower end, and by shifting the key vertically in the recess it may accommodate itself to the diameter of the sucker rod for firm gripping engagement therewith when the set screw is tightened. This also provides the key with shoulders 29 for resting upon the upper face of the block at the upper end of the recess 25 and supporting the key so that it may not accidentally drop downwardly through the recess and be lost if the set screw works loose. The diameter of the wheel is so much greater than that of the sucker rod that when the wheel is grasped by its rim or outer end portions of its spokes the leverage exerted will cause sections of the string of sucker rods to be readily loosened and unscrewed from each other.

When the wheel is turned in a direction to unscrew the section of the sucker rods from each other, it is desired to permit the wheel to be turned a partial rotation and then be held against retrograde rotation. In order to do so there has been provided a latch 30 which extends circumferentially of the wheel in the channel 31 of a latch housing or bracket 32. This housing or bracket is mounted against the under face of the plate 14 by screws 33 which are passed upwardly through openings in the flange 34 of the bracket and into threaded openings formed in the plate. Therefore, the bracket or housing is removably mounted and by detaching the housing the latch may be set into the housing with its end carrying the upstanding bill 35 projecting from either side of the housing desired and hold the wheel against free turning in either a right-hand or left-hand direction.

The latch is pivotally mounted by a pin 36 passed through aligned openings 37 at one side or the other of the housing and a spring 38 formed from a strip of resilient metal urges the latch up-

wardly so that while the latch may be depressed and allow the spokes to pass over its bill as the wheel is turned in a direction to unscrew sucker rods from each and then return to its normal position for engaging side portions of the spokes and prevent retrograde rotation of the wheel.

In some cases it is desirable to prevent even limited retrograde rotation of the wheel and maintain as much torque upon the string of sucker rods as possible, therefore there has been provided a brake shoe or block 39 which is disposed against the inner side face of the bracket 32 between guide blocks 40 held to the bracket 32 by screws 41. A shaft 42 is rotatably mounted through the lower portion of the bracket midway the width thereof and has its outer end portion protruding from the bracket and carrying a handle or lever 43 for turning the shaft. The inner end portion of the shaft also protrudes from the bracket and carries an eccentric block or cam 44 passing through a circular opening formed in the brake shoe 39.

Normally, the shoe is in a lowered position out of contact with the under surface of the ring 9 but when the handle 43 is grasped and the shaft 42 turned the shoe will be shifted upwardly and its upper end, which is formed with a side flange 45, brought into binding engagement with the under surface of the ring and firmly grip the ring to prevent turning of the wheel.

While I have shown the preferred embodiment of my invention, it is to be understood that various changes in the size, shape and arrangement of parts may be resorted to without departing from the spirit of the invention and the scope of the appended claims.

Having thus described the invention, what is claimed is:

1. A tool for backing off sucker rods comprising a wheel, there being an opening at the center of the wheel and a radially extending slot leading from the outer edge of the wheel to the opening, a depending annular collar carried by said wheel and formed with a channel about its outer peripheral edge face and with a radially extending slot registering with the slot of the wheel, a ring fitting about said collar within the channel thereof and rotatably supporting the collar and the wheel and formed with a slot for registering with the slots of the collar and the wheel whereby a sucker rod may be passed through the slots and into the center opening of the wheel and dispose the wheel about the sucker rod concentric thereto, a stationary jaw carried by said wheel, a block removably carried by the stationary jaw and extending across the slot of the wheel, confronting faces of the block and the jaw being formed with recesses for receiving a portion of the sucker rod, a key passing vertically through the recess of the block and having an inner edge face confronting the sucker rod, an abutment being provided upon the key for engaging the block and limiting downward movement of the key through the recess in the block, a set screw threaded through an opening in the block engaging the outer edge face of the key for forcing the key into gripping engagement with the sucker rod and causing the sucker rod to be turned with the wheel, an arm extending radially from said ring and adapted to be connected with means for holding the arm and the ring stationary, a latch carried by said arm for allowing rotation of the wheel in a direction to loosen sucker rods and releasably hold the wheel against retrograde rotation, and a brake movable

into position for engaging said collar and holding the wheel stationary.

2. A tool for backing off sucker rods comprising a wheel having a hub and a rim and spokes extending between the hub and the rim, there being an opening at the center of the hub and a slot leading from the outer edge of the rim to the opening in the hub, a collar carried by said wheel concentric thereto and formed with a slot registering with the slot of the wheel, a ring fitting about said collar for rotatably mounting the collar and the wheel, said ring being formed with a slot for registering with the slots of the collar and the wheel and allowing sucker rods to be passed inwardly through the slots and into the opening in the hub and dispose the wheel about a sucker rod concentric thereto, a stationary jaw carried by said hub and formed with a recess registering with the opening in the hub for receiving a portion of a sucker rod, flanges extending from opposite ends of said stationary jaw, a block fitting against the recessed side of said stationary jaw and formed with hooked end portions engaging about the flanges of the stationary jaw and with a recess registering with the recess of 25

the stationary jaw, a key extending vertically through the recess of the block and having a toothed side face for gripping a sucker rod, a set screw threaded through an opening in said block with its inner end abutting said key for forcing the key into gripping engagement with the sucker rod, and means allowing rotation of the wheel in a direction for backing off sucker rods and releasably holding the ring against uncontrolled retrograde rotation.

FRANK AUSTIN.
